UNITED STATES PATENT OFFICE

HOWARD J. KERR, OF EL MORA, NEW JERSEY, ASSIGNOR TO THE BABCOCK & WILCOX COMPANY, OF BAYONNE, NEW JERSEY, A CORPORATION OF NEW JERSEY

WATER-TUBE BOILER

Application filed December 28, 1923, Serial No. 683,127. Renewed November 17, 1930.

My present invention relates to water tube boilers having horizontally inclined water tubes in which provision is made for preventing or minimizing the accumulation of slag on the tubes.

My invention will be best understood from the following description and the annexed drawings in which Fig. 1 is a sectional side elevation of an illustrative form of water tube boiler in which one form of my invention is embodied; Fig. 2 is a section on the line 2—2 of Fig. 1; Fig. 3 is an enlarged rear view of a portion of Fig. 1; Fig. 4 is a vertical section on the line 4—4 of Fig. 3; Fig. 5 is a section on the line 5—5 of Fig. 3; Fig. 6 is a view similar to Fig. 1 showing a modification; Fig. 7 is a section on the line 7—7 of Fig. 6; Fig. 8 is a view similar to Fig. 6, showing still another modification; Fig. 9 is a section on the line 9—9 of Fig. 8; Fig. 10 is a partial sectional elevation of a water tube boiler, showing still another modification, Fig. 11 being a section on the line 11—11 of Fig. 10; Fig. 12 is a partial sectional side elevation of a water tube boiler, showing another form, Fig. 13 being a section on the line 13—13 of Fig. 12; Fig. 14 is a sectional side elevation of the lower part of a water tube boiler showing a method of installing my invention in boilers already built, Fig. 15 being a section on the line 15—15 of Fig. 14.

Like reference characters indicate like parts in the several views.

As is well known, particularly when certain types of forced-blast stokers are used with certain grades of fuel, molten particles of slag-producing material are carried up from the surface and on contacting with the boiler tubes, adhere thereto in a more or less plastic condition which gradually hardens and closes the passages between the tubes. It has heretofore been proposed to avoid this difficulty by opening up the flow spaces through the lowermost rows of tubes in a water tube boiler having horizontally inclined tubes, to reduce the velocity of the gases through such lowermost tubes below what it would be with the usual arrangement, and my present invention relates to such

structures in which the tubes in the lowermost rows are arranged so as to give this reduced velocity more effectively, and so that the spaces between the tubes will not readily become clogged by slag which may accumulate on the tubes. 55

I have found that I can arrange the tubes in the lowermost rows so that the tubes in successive rows are either directly over each other or have a staggered relation, provided the vertical distance between the rows or the horizontal spaces between the tubes in the same rows or both are properly arranged. 60

I have found that when the tubes in the lowermost rows are staggered but with a tube in an upper row only a relatively short distance above or to one side of a tube in the next lower row, the slag particles will collect on the bottom of such upper tube and gradually extend downwardly in a more or less plastic condition until it touches the tube in the lower row or even may be forced over against such tube by the draft. As soon as contact is made, the plastic slag chills to a degree and closes the passage between such upper and lower tubes. 75

By my invention I arrange the tubes in two successive rows, as, for instance, the lowermost row and the one above it, not only so that the deposit of slag will be reduced 80 due to the reduction of the velocity of the gases, but also in such a way that any accumulation of slag on the tubes of the lowermost rows, as it extends downwards, will not form a continuous bridge across the flow 85 spaces, since the accumulation will tend to drop from the tube before it reaches to the next lower tube, and in thus dropping off, it will either clear the lower tube entirely or else will temporarily bridge the space between a pair of tubes in the lower row from which it may be quickly melted therefrom by the contact of the flame. 90

Referring now to the arrangement of tubes shown in Figs. 1 and 2, the boiler shown is 95 of the well-known type having uptake headers or water compartments 10 and 11 connected by nipples 12 and downtime headers or water compartments 13 and 14 connected by nipples 15. Between the water compart- 100

ments is a main bank of tubes 16 separated from a group of tubes 17 by a space in which is located a superheater 18 supplied by steam from the water drum 19, in the usual manner, this water drum being connected to the end of the compartments, also in the usual manner. A horizontal baffle 20 extends along the tops of the tubes 17 and the superheater 18 to an inclined baffle 21 to form between it and the compartment 10, a transverse gas pass across the main bank, a second cross baffle 22 directing the gases back and forth across the tubes to the gas outlet.

In the form shown, a special water compartment 23 is located below the uptake headers 11 and connected thereto by nipples 24. Spaced from the tubes 17 and from each other are three rows of tubes 25, 26 and 27, the latter extending from the special water compartment 23 to the downtake header 14. Below the tubes is a furnace chamber 28 provided with a forced-blast underfeed stoker 29, the chamber 28 being arranged so that substantially the entire length of the lowermost tubes are exposed to the radiant heat of the furnace.

As shown in Fig. 2, in the form illustrated in Fig. 1, the tubes in the group 17, as is also true of the group of tubes 16, are arranged in the usual manner, with the rows spaced relatively closely in a vertical direction and the tubes in successive rows being staggered, as is also the usual arrangement, in order to obtain the best heat transfer.

As will be seen by an inspection of Fig. 2, the tubes in the rows 25, 26 and 27 are also staggered relatively to each other in successive rows, but the vertical distances between the row centers or between the tops of the tubes in one row and the bottoms of the tubes in the next higher row are much greater than the corresponding distances in the tube arrangement in the main bank. As illustrated, the distance between the center lines of the rows of slag screen tubes is equal to a multiple of the distance between the planes of the center lines of two adjacent rows of tubes in the main bank.

When slag particles are carried upward with the gases, such particles as pass between the tubes in the row 27, strike the tubes either of the row 26 or the row 25 and collect thereon, as described above, this accumulation gradually extending downward in a plastic condition. By making the distance between the rows relatively great and preferably, as I have found by experience, providing a space between the tops and the bottoms of adjacent rows equal to at least a tube diameter, sufficient space is provided so that the accumulation of slag will drop off of an upper tube before its lower end contacts with a tube in the next lower row. When the tubes are staggered, as shown in Fig. 2, slag may drop, for instance, from one of the tubes in row 26

and will fall into the space between a pair of tubes in the row 27. It may in some instances adhere to the tubes 27, but such adherence is usually only temporary, because this slag will then be subjected to the intense heat of the flame and will be heated to such a high temperature that it will melt and drop off into the furnace.

If the accumulation of slag is so great that in the course of time some of the flow spaces between the lowermost tubes become clogged, it is desirable to provide means to permit the lowermost tubes to be cleaned conveniently. To this end, I preferably make the uptake water compartments so that a cleaning tool may be inserted to scrape the accumulated slag from the tubes. In connection with the boiler shown in Fig. 1, I have provided an illustrative arrangement to this end which is best shown in Figs. 3, 4 and 5.

In this arrangement, a series of metallic plates 30 are held to the nipples 24 by U-shaped members 31. Each of the plates 30 is provided with an opening 32 having a cover 33 of a known type, which can be raised and held in its raised position, so that a cleaning tool may be inserted through the opening 32 and between a pair of nipples 24 to scrape the accumulated slag from the tubes 26 and 27. The space above the opening 32 may be filled with any suitable plastic material 34.

In the arrangement shown in Fig. 6, the uptake water compartments 35 and the downtake water compartments 36 are connected by a main bank of water tubes 37 which are staggered in the usual manner, as shown best in Fig. 7, these water compartments 35 and 36 being connected to a cross drum 38, in the usual manner, from which drum steam passes to a superheater 39 placed above the main bank.

Below the main bank of tubes 37 are three rows of tubes 40, 41 and 42, the rows 40 and 41 being spaced from the main bank 37 but having the usual staggered relation to each other, as shown best in Fig. 7, and the row 42 extending from a special water chamber 43 connected to the uptake headers by nipples 44, the row 42 being spaced a considerable distance below the row 41. A horizontal baffle 45 extends along the row 40 and joins a vertical cross baffle 46 extending across the space between the main bank and the row 40. A short horizontal baffle 47 extends along the lowermost rows of tubes in the main bank to join a vertical baffle 48 extending across the main bank. A second vertical baffle 49 directs the gases to the gas outlet.

The furnace chamber 50 extends beneath the water tubes, the latter being exposed for the major portion of their length to the radiant heat from the furnace, the furnace having in this instance a pair of forced-blast underfeed stokers 51 oppositely disposed.

As will be seen in Fig. 7, the row 42 is wide-

ly spaced from the next upper row 41 so that although the tubes in these two rows are staggered relatively to each other, nevertheless the slag accumulating on the tubes of row 41 can-
5 not readily bridge across the two rows.

In the arrangement shown in Fig. 8, the uptake water chambers 52 and downtake water chambers 53 are connected by a main bank of tubes 54, the water chambers being, in turn, 10 connected to the drum 55 in the usual manner, and a superheater 56 located above the main bank, receiving steam from the drum 55. The tubes in the main bank have the usual 15 staggered arrangement, as shown best in Fig. 9.

Below the main bank and spaced therefrom are three rows of tubes 57, 58, and 59, the tubes 59 extending from a special water chamber 60, connected to the uptake water chambers 52 by nipples 61 and at the opposite end extending into a mud drum 62, connected by nipples 63 to the downtake water chambers. The space between the rows 59 and 58 is relatively great, and in this form I have also 20 increased the space between the rows 58 and 57, particularly at the entrance to the first transverse pass across the main bank formed by the inclined baffle 64, by bending the centers of the tubes 58 downward, as shown best 25 in Fig. 8. Above the tubes 57 is a horizontal baffle 65 extending to the lower end of the baffle 64 and a transverse baffle 66 directs the 30 gases to the gas outlet.

In this arrangement, as shown best in Fig. 35 9, in order to open up the spaces between the lowermost rows of tubes still further, as may be desirable in some instances, I have made the horizontal spaces between the walls of adjacent tubes of each of the two lowermost 40 rows very much wider than usual, the tubes preferably being spaced at least double the horizontal distance between the tubes in the main bank, and I also preferably arrange the tubes in the two lowermost rows in staggered 45 relation so that as slag accumulates on the tubes of the row 58 and falls, it will not strike the tubes of the row 59 but will fall directly into the furnace chamber.

In this arrangement, while I have shown 50 the space between the rows 58 and 59 as relatively large, it will be understood that with a sufficient lateral spacing between the walls of adjacent tubes in at least the two lowermost rows, the vertical spacing of these rows 55 can be greatly reduced, and in fact, if desired, may in some instances be no greater than the vertical spacing in the tubes in the main bank, provided that no tube in the lowermost row is sufficiently near to the path of accumulated slag extending down or falling from 60 a tube in the next higher row to permit contact of such slag with a tube in the next lower row to bridge over the flow spaces.

In Figs. 10 and 11 I have shown still another modification which is particularly

adapted for application to boilers built in the usual manner and in which slagging difficulties develop. The uptake water chambers 67 and the downtake water chambers 68 are connected by a main bank of staggered tubes 69 (only two rows of which are illustrated) and the boiler has a horizontal baffle 71 and a transverse baffle 72, also of the well-known type.

Below the main bank is a row of tubes 73 75 spaced in the usual manner and below the row 73 are what is essentially two rows 74 and 75, so far as the space beneath the first transverse gas passage across the main bank of tubes 69 is concerned, these two rows being 80 formed, however, by lowering the right-hand end in Fig. 10 of each alternate tube, so that at the left-hand end of Fig. 10, the ends of the tubes in the rows 74 and 75 are in the same horizontal plane and enter each of the headers, as shown in Fig. 11, but the lowered tubes of the row 75 enter a special water compartment 76, connected by nipples 77 to the uptake headers 67 and the remaining tubes enter directly into the uptake header 67. It 85 will be seen from this arrangement that in the portion of the boiler directly beneath the first pass, at which place I have found the collection of slag is most likely to occur, there is provided a pair of rows of tubes in 90 which the tubes are staggered relatively to each other but in which the horizontal distance between adjacent tubes in each row is very much wider than the horizontal distances between tubes in the rows in the main 95 bank 69.

In the arrangement shown in Fig. 12, the uptake water compartment 78 and downtake water compartment 79 are connected by a main bank of staggered tubes 80 and below the main bank are three rows of tubes 81, 82 and 83, the latter extending between a special water compartment 84 connected by nipples 85 to the uptake water compartments 78 and at the other end the rows 83 being connected to the usual mud drum 86, connected to the downtake water compartments 79. The row of tubes 83 is spaced a considerable distance below the row 82, the rows 81 and 82 having the usual spaced and staggered relation of the main bank and the tubes in the row 83 being staggered in relation to the tubes in the row 82.

In Figs. 14 and 15, I have shown an arrangement which may be applied to boilers already built, in which the headers are continuous and in which originally there were two rows of tubes spaced from the main bank but having the usual staggered relation and the usual spaced relation. In such case I leave the lowermost row 87 extending between the uptake headers 88 and the downtake headers 89 and remove the row which would normally engage with the steps 90 in the respective headers and substitute therefor a row 91 with their ends bent as shown best in Fig. 14, so 125 130

as to enter at right-angles with the plain portions of the headers 88 and 89, at the same time, arranging the tubes 91 so that the vertical distance between it and the row 87 will be much greater than usual. In this arrangement, as shown best in Fig. 15, I have shown the tubes 91 as positioned directly above the tubes 87, but, as I have pointed out above, this is not essential, since the distance between the two lowermost rows may be made sufficient to prevent the closing up of the gas passages. By placing one row above the other, however, it is obvious that the distance between the rows 87 and 91 need not be as great as would be necessary if the tubes were staggered.

It will be understood that the embodiment of my invention may be widely varied and that the forms shown are merely illustrative.

20 It will also be understood that the separate water compartment beneath the uptake headers, which I have shown in some of the figures, may be of any desired form and may have a plurality of water tubes entering it instead of only one, as shown. By providing the spaces formed between the nipples connecting such special compartment with the uptake headers with openable covers, cleaning tools may be inserted irrespective of the 25 number of tubes below such nipples, so that the lower tubes of the first pass may be readily cleaned.

I claim:

1. A water tube boiler having a furnace 35 provided with a type of firing apparatus which causes slag particles to rise with the gases entering the water tubes, said boiler having a bank of water tubes arranged in rows extending across the bank with the 40 ends of the water tubes connected to water compartments, and a plurality of rows of slag screen water tubes between the furnace and said bank, with the distance between the planes of the center lines of said rows of slag screen tubes, for at least a portion of the 45 length of the tubes, equal to a multiple of the distance between the planes of the center lines of two adjacent rows of tubes in said bank.

50 2. A water tube boiler having a furnace provided with a type of firing apparatus which causes slag particles to rise with the gases entering the water tubes, said boiler having a bank of water tubes arranged in 55 rows extending across the bank with the ends of the water tubes connected to water compartments, and a plurality of rows of slag screen water tubes between the furnace and said bank, having diameters at least as great as the diameters of the tubes in said bank and with the 60 distance between the planes of the center lines of said rows of slag screen tubes, for at least a portion of the length of the tubes, equal to a multiple of the 65 distance between the plane of the center

lines of two adjacent rows of tubes in said bank.

3. A water tube boiler having a furnace provided with a type of firing apparatus which causes slag particles to rise with the 70 gases entering the water tubes, said boiler having a bank of water tubes with their ends connected to water compartments, and a plurality of rows of slag screen water tubes between the furnace and said bank having 75 diameters at least as great as the diameters of the tubes in said bank and with the tubes in the row nearest the furnace staggered in relation to the adjacent row and with the distance between the planes of the center lines 80 of said rows, for at least a portion of the length of the tubes, equal to at least two tube diameters.

4. A water tube boiler having a furnace provided with a type of firing apparatus 85 which causes slag particles to rise with the gases entering the water tubes, said boiler having a bank of water tubes with their ends connected to water compartments, and a plurality of rows of slag screen water tubes 90 between the furnace and said bank having diameters at least as great as the diameters of the tubes in said bank and with the tubes in the row nearest the furnace staggered in relation to the adjacent row and with the 95 distance between the planes of the center lines of said rows, for at least a portion of the length of the tubes, equal to at least two tube diameters, the center-to-center distance between the tubes in said rows, measured in 100 said planes, being equal to at least two tube diameters.

5. A water tube boiler having a furnace provided with a type of firing apparatus 105 which causes slag particles to rise with the gases entering the water tubes, said boiler having a bank of water tubes with their ends connected to water compartments, and a plurality of rows of slag screen water tubes 110 between the furnace and said bank having diameters at least as great as the diameters of the tubes in said bank and with the tubes in the row nearest the furnace staggered in relation to the adjacent row, the center-to-center distance between the tubes in said 115 rows, measured in the planes of the diameters of the tubes in each row, being equal to at least two tube diameters.

6. A water tube boiler having a furnace provided with a type of firing apparatus 120 which causes slag particles to rise with the gases entering the water tubes, said boiler having a bank of water tubes with their ends connected to water compartments, and a plurality of rows of slag screen water 125 tubes between the furnace and said bank having diameters at least as great as the diameters of the tubes in said bank and with the tubes in the row nearest the furnace staggered in relation to the adjacent row, the center-to- 130

center distance between the tubes in said rows, measured in the planes of the diameters of the tubes in each row, being equal to at least two tube diameters, and the tubes in the second row from the furnace being positioned relatively to the tubes in the first row from the furnace so that vertical planes tangent to the sides of the tubes in the second row will pass between tubes in the first row.

10. 7. A water tube boiler having a furnace provided with a type of firing apparatus which causes slag particles to rise with the gases entering the water tubes, said boiler having a bank of water tubes with their ends

15 connected to water compartments, and a plurality of rows of slag screen water tubes between the furnace and said bank, with the tubes in one of said rows bent between the ends of said tubes in a direction away from

20 the tubes in the other of said rows to provide a greater distance between said rows for a portion of the length of the tubes than between the ends of the tubes in the two rows.

8. A water tube boiler having a bank of 25 horizontally inclined water tubes connecting water compartments at front and rear, over which the furnace gases pass, a plurality of rows of water tubes below said bank and spaced a substantial distance therefrom, the 30 two lowermost rows having the tubes therein spaced apart horizontally at least double the distance that the tubes of said bank are spaced apart horizontally, and being arranged in staggered relation to each other so that slag 35 which accumulates on the tubes of the second row will, on falling, pass into the furnace without striking the tubes of the lowermost row.

9. A water tube boiler having a bank of horizontally inclined water tubes connecting water compartments at opposite ends thereof, over which the furnace gases pass, a plurality of rows of water tubes disposed below said bank and spaced a substantial distance therefrom, the two lowermost rows having the tubes therein disposed substantially at equal distances apart in each row, said distances being at least double the distance that the tubes of said bank are spaced apart horizontally, and the tubes in said two rows being arranged in staggered relation to each other so that slag which accumulates on the tubes of the second row will, on falling, pass into the furnace without striking the tubes of the 55 lowermost row.

10. In combination, a furnace having firing apparatus of the type which causes slag particles to rise with the rising gases, a water tube boiler disposed above said furnace and 60 having a bank of horizontally extending inclined water tubes connecting water compartments at the front and rear, a plurality of rows of water tubes below said bank and exposed to radiant heat of said furnace for the 65 major portion of their length, said lower rows

of water tubes being spaced apart a greater distance than the rows of the bank, a superheater disposed in a space beyond the bank of water tubes and in position to be contacted with by the gases after they leave the bank of water tubes, said water tubes being sufficient in number to cause substantially thorough mingling and subsequent combustion of the gases before they reach the superheater, and steaming water tubes beyond the superheater 70 and in position to be heated by the gases after they leave the superheater.

HOWARD J. KERR.
